(57) **CLAIM**

The ornamental design for a solar LED wall light, as shown and described.

DESCRIPTION

FIG. 1 is a front view of a solar LED wall light of the present invention.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a perspective view thereof.

FIG. 8 is a second perspective view thereof.

FIG. 9 is a third perspective view thereof; and,

FIG. 10 is further perspective view of the solar LED wall light where an upper front portion of the solar LED wall light is in an open configuration.

The broken line showing of certain portions of the solar LED wall light is included for the purpose of illustration only and forms no part of the claimed design.
